UNITED STATES PATENT OFFICE

2,566,900

ULTRA HIGH FREQUENCY ANTENNA SYSTEM

Elmer D. McArthur, Schenectady, N. Y., assignor
to General Electric Company, a corporation of
New York

Application December 31, 1948, Serial No. 68,607

2 Claims. (Cl. 250—33.65)

1

My invention relates to antenna systems for radiation of ultra-high frequency electromagnetic waves, and more particularly to antenna systems employing parabolic reflectors for the directive propagation of ultra-high frequency radiation.

An object of my invention is to provide a new and improved device for illuminating a parabolic reflector which is of simple construction and easily mounted on the end of a wave guide.

An additional object is to provide an illuminating device for an antenna system of the above type which reduces undesirable reflections from the wave guide across the face of a parabolic reflector.

In general, my invention comprises a conductive horn closed at its narrower end and facing a parabolic reflector substantially at the focal point thereof. The horn is fed by a wave guide extending through the center of the reflector and aimed at the closed end of the horn. A septum secured to opposing sides of the open end of the guide functions to support the horn in its proper position.

For a more complete understanding of my invention, reference should be made to the accompanying drawing in which Fig. 1 is a sectional view of an illuminating device constructed in accordance with my invention; Fig. 2 is a perspective view illustrating a method of mounting the illuminating device of Fig. 1 on an end of a wave guide; Fig. 3 is a sectional view illustrating the use of the illuminating device of Fig. 1 in conjunction with an antenna system employing a parabolic reflector; and Fig. 4 is a sectional view of an antenna system similar to Fig. 3, but incorporating a modification of my invention whereby variations in the radiation pattern may be obtained.

Referring to Fig. 1, I have shown my invention in one form as applying to a rectangular wave guide 1 which represents an output guide from an ultra-high frequency transmitting system. A flared horn-shaped conductive member 2 is mounted on the end of wave guide 1 by a flat plate or septum 3 inserted within wave guide 1 along the longitudinal axis thereof and parallel to the pair of opposing walls of the wave guide which happen to be of greater dimensions. The septum 3 is secured to the other pair of opposing interior walls by any suitable means such as welding. One end of septum 3 extends beyond the open termination of wave guide 1 and is secured to a conductive transverse central wall 4 of member 2. The sides of member 2 extend

2

angularly back from wall 4 over the end of wave guide 1 to form an inverted horn of rectangular cross section which faces a parabolic reflector 6 as illustrated in Fig. 3. Wave guide 1 extends through the center of reflector 6 and is terminated substantially as the focal point thereof.

The illuminating device described above, comprising wave guide 1, conductive member 2 and septum 3, is particularly adapted for use with a rectangular wave guide employing a transverse electric mode of wave propagation of the first order denoted as a TE_{10} wave. In a wave of this type, no field components vary in the vertical or y direction, and the only electrical field component is the one passing between the top and bottom of the guide. The corresponding charges induced by the varying electrical field range from zero along the side walls of wave guide 1 to maximum at the center of the top and bottom conductive walls. The magnetic field, forming closed paths around the electrical displacement currents arising from the electrical field, causes both a longitudinal current flowing along the top and bottom of the guide and a current from top to bottom around the periphery of the guide.

The septum 3, therefore, in this mode of operation, does not substantially affect the wave propagation through the guide since it is connected between points of zero electrical charge and through an area of the guide where there is no concentration of magnetic flux. As illustrated by the electrical vectors A of Fig. 1, the direction of the electrical field is not affected by its passage through the septum 3. The total wave is reversed by conductive member 2 without changing the phase relation of the radiation pattern on either side of the septum 3. The parabolic reflector 6 receives the total wave in the same manner as if it had been directly illuminated by a completely open horn facing the reflector.

Referring now to Fig. 4, I have shown a modification of my invention whereby a variation in the focal angle of illumination can be obtained. An angular conductive collar or flange 7 surrounds the open end of wave guide 1 and extends back over the guide. The sides 5 of conductive member 2 are flared at a greater angle than in Fig. 1 thereby maintaining the relative dimension, d , of the mouth of the horn in order to properly match the impedance of the radiating device to that of free space. The greater flare angle results in a variation of the radiation pattern produced by the antenna system. Many different patterns of radiation can, of course, be

obtained by varying either the flare angle or the dimensions of conductive member 2.

While I have shown a particular embodiment of my invention, it is to be understood that I do not wish to be limited thereto since many modifications may be made, and I, therefore, contemplate by the appended claims to cover all such modifications as fall within the true spirit and scope of my invention.

What I claim as new and desire to secure by Letters Patent of the United States is:

1. In an antenna system of the type employing a parabolic reflector, means for illuminating said reflector comprising a rectangular wave guide extending through the center of said reflector and having an open end substantially at the focal point thereof, a conductive horn-shaped member having a transverse central wall facing said open end and having angular sides extending back over said end, and a conductive septum secured to and extending normal to said central wall and inserted along the longitudinal axis of said guide in a plane parallel to the pair of walls thereof having principal dimensions, said septum extending and secured within said guide to the other pair of walls thereof.

2. In an antenna system, a parabolic reflector, a rectangular wave guide extending through said reflector and having an open end substantially at the focal point thereof, a conductive horn-shaped member having a transverse central wall facing said open end and having angular sides extending back over said end, and a conductive septum secured to and extending normal to said central wall and inserted along the longitudinal axis of said guide in a plane parallel to the pair of walls thereof having principal dimensions, said septum extending and secured within said guide to the other pair of walls thereof.

portion of said guide and angularly extending back from said open end, a conductive rectangular horn having a transverse central wall facing said open end and having angular sides extending over said collar in spaced relation therewith, and a flat conductive plate secured to and extending normal to said central wall and inserted along the longitudinal axis of said guide in a plane parallel to the pair of walls thereof having principal dimensions, said plate extending and secured within said guide to the other pair of walls thereof.
